UNITED STATES PATENT OFFICE

158,044

LOG AND WOOD CART

Algol J. Bowman, Monmouth, Ill.

Application May 13, 1949, Serial No. 2,622

Term of patent 3½ years

(Cl. D14—3)

To all whom it may concern:

Be it known that I, Algol J. Bowman, a citizen of the United States, residing at Monmouth, in the county of Warren and State of Illinois, have invented a new, original, and ornamental Design for a Log and Wood Cart, of which the following is a specification, reference being had to the accompanying drawing, forming a part thereof.

I claim:

The ornamental design for a log and wood cart, as shown.

ALGOT J. BOWMAN.
